UNITED STATES PATENT OFFICE.

CHARLES HENRY COLE, OF BALTIMORE, MARYLAND.

DOOR STOP AND HOLDER.

SPECIFICATION forming part of Letters Patent No. 752,375, dated February 16, 1904.

Application filed September 21, 1903. Serial No. 174,106. (No model.)

To all whom it may concern:

Be it known that I, CHARLES HENRY COLE, a citizen of the United States of America, and a resident of Baltimore city, in the State of Maryland, have invented certain new and useful Improvements in Door Stops and Holders, of which the following is a specification.

My invention relates to improvements in door-stops which hold doors when open and prevent closing of the door by the wind or jarring or settling of the building.

The objects of my invention are to provide a new and improved door stop and holder, also to provide an adjustable or extensible stop which could be so made of standard size and adjusted to correspond with the door-knob to prevent said knob striking or injuring the wall.

Referring to the accompanying drawings, Figure 1 is a sectional side elevation of my improved door stop and holder shown as connected and holding the door open. Fig. 2 is a front view of the catch. Figs. 3 and 4 are respectively front and side elevation of a modification of the catch.

As it is a well-known fact that door-knobs are used and are of different sizes, it is not thought necessary to illustrate said door-knob.

Similar numerals refer to similar parts throughout the drawings, in which—

1 is the washboard of wall, to which the stop 3 is secured by the screw 2. This stop 3 may be hollow to receive the extensible and adjustable portion 6, which is held in the various positions by the pin 4 passing through the perforation 5 in the stop and through any one

of the several perforations 7 8 9 10 in the adjustable portion 6. As the outer end of this adjustable portion 6 is a suitable head or knob 11, which passes into the opening 15 of a suitable catch 13, which catch is in turn held by its frame 14 and the screw 18 to the door 17, 15' being the hole in the frame 14 through which screw 18 passes. Catch 13 is preferably made of sheet spring-steel, with a central orifice 15 and suitable stop 16; but it is not desired to limit myself to the particular construction shown. The head or knob 11 may be provided with the usual rubber cushion 12; but it is not deemed necessary to use this cushion.

I am aware that it is common to use a door-stop and a catch on the door-stop adapted to secure a knob on the door; but this I do not claim.

What I claim as my invention is—

1. A door-stop comprising a base and telescoping parts provided with a perforation adapted to receive a pin for securing the telescoping parts together, substantially as described.

2. In a catch, a disk having a central orifice with radial slots and adapted to engage a knob, substantially as described.

Signed by me at Baltimore city, Maryland, this 19th day of September, A. D. 1903.

CHARLES HENRY COLE.
